ATTY.

UNITED STATES PATENT OFFICE.

GEORGE E. MILLER, OF STEGE, CALIFORNIA.

SAW-HANDLE FASTENER.

1,303,492.

Specification of Letters Patent.

Patented May 13, 1919.

Application filed August 16, 1915. Serial No. 45,627.

To all whom it may concern:

Be it known that I, GEORGE E. MILLER, citizen of the United States, residing at Stege, county of Contra Costa, State of California, have invented certain new and useful Improvements in Saw-Handle Fasteners, whereof the following is a specification.

This invention relates to means for fastening the handles and blades of saws together.

In carrying out the invention I aim to provide a more simple fastening than has heretofore been used and one so constructed as to simplify the act of connecting and loosening the blade and handle; also to reduce the number of fastenings.

To these ends I make use of a single transverse bolt or pin which engages a notch in the saw blade, and, toward the other side 20 of the blade I make use of a longitudinal bolt or pin which is slotted to receive the blade and provided with means for engaging the blade and with means for drawing it tight.

25 In the accompanying 1 sheet of drawings I have illustrated my invention as applied to a carpenter's hand saw.

In the drawings:

Figure 1 is an elevation showing the handle and a portion of a saw blade, the handle being partially cut away and sectioned to more perfectly show one of the fastening means.

Fig. 2 is a transverse section on the line 35 *a, a*, of Fig. 1, looking in the direction of the arrow.

Fig. 3 is a section of the longitudinal fastening bolt showing also in section the saw blade therein.

40 Fig. 4 is a transverse section taken on the line *b, b*, of Fig. 3.

In the figures: 1 represents a saw handle which may be of the ordinary form, and 2 is the saw blade. 3 is a notch in the upper 45 edge of the saw blade shown in Fig. 2 and dotted lines in Fig. 1. 4 is a bolt passing transversely through the handle, 1, and in a position to engage the notch, 3. 5 is a longitudinal fastening bolt provided with a 50 nut, 6. This bolt passes through a hole, 7, in the handle, 1. The nut, 6, rests in a notch, 8, cut in the hand hole, 9, of the handle for that purpose, so that the nut, 6, and the end of the bolt, 5, will be out of the 55 way of the fingers in grasping the handle.

The bolt, 5, is provided with a longitudinal slot or kerf, 10, shown more particularly in Fig. 3. This slot is of a width to receive the saw blade, 2. 11 is a hole through the saw blade at any convenient point of that 60 part which enters the slot, 10. 12 is a latch which engages the hole, 11, and is pressed into it by the spring, 13, which may be fastened by a screw, as 14.

In connecting the handle to the blade, the 65 bolt, 5, is entered in the hole, 7, and the blade is then inserted in the usual kerf in the handle provided to receive it and its notch, 3, engages with the bolt, 4, the blade is then swung upon the bolt, 4, as a pivot 70 until its edge enters the kerf, 10, in bolt, 5, and the latch, 12, engages the hole, 11, in the blade. The bolt 5, is then pushed on through the hole, 7, and the nut, 6, applied to it and tightened, drawing the blade firmly to its 75 seat in the handle.

To disengage the blade and handle, the nut, 6, is first loosened or removed and the bolt, 5, then pushed longitudinally until the latch, 12, disengages the hole, 11, in the 80 blade, 2. The blade may then be removed from the handle by simply reversing the movements by which it was applied. When the blade is drawn tightly to its seat and the spring, 13, will be within the hole, 7, 85 in the handle and this will act as a lock to the latch, 12, and effectually prevent accidental disengagement.

Having thus described my invention, and an embodiment of it, in the full, clear and 90 exact terms required by law, and knowing that it comprises novel, useful and valuable improvements in the art to which it pertains, I here state that I do not wish to be limited to the precise construction and arrangement 95 of the several parts, as herein set forth, as the same may be variously modified by a skilled mechanic without departing from the spirit of the invention.

What I claim and desire to secure by Letters Patent of the United States is the following, to wit:—

1. A saw handle fastening device, comprising in combination with a blade and handle, said blade provided with a vertical slot in its back edge and a hole near its toothed edge, a transverse holding bolt on said handle engaging said slot and a longitudinal slotted bolt entirely in said handle adapted to receive said blade, a spring latch 105 110

on said bolt engaging automatically said hole and holding said blade within said slot.

2. A saw handle fastening, comprising, in combination with a blade and handle, a slot in the back edge of the blade, a fastening bolt adapted to engage said slot, a longitudinal bolt near the toothed edge of the blade, said bolt being slotted to receive the blade, said blade having a hole through it,

and a latch applied to the bolt and adapted to engage said hole.

In testimony that I claim the foregoing I have hereto set my hand in the presence of two witnesses, this 10th day of August, 1915.

GEORGE E. MILLER.
